(57) **CLAIM**

The ornamental design for a combined spray dispenser and cap, as shown and described.

DESCRIPTION

FIG. 1 is a perspective view of a combined spray dispenser and cap showing my new design;

FIG. 2 is a top plan view thereof;

FIG. 3 is a front elevational view thereof, the rear being a mirror image;

FIG. 4 is a left side elevational view thereof, the right side being a mirror image;

FIG. 5 is a bottom plan view thereof;

FIG. 6 is an exploded perspective view thereof;

FIG. 7 is a top plan view of the spray dispenser shown without the cap for completeness of illustration;

FIG. 8 is a rear elevational view thereof;

FIG. 9 is a right elevational view thereof;

FIG. 10 is a front elevational view thereof; and,

FIG. 11 is a left elevational view thereof.
